UNITED STATES PATENT OFFICE.

WILLIAM ERNEST BENN, OF MCADAM JUNCTION, NEW BRUNSWICK, CANADA, ASSIGNOR
OF ONE-HALF TO GEORGE ELDEN DAVIS, OF DEBEC JUNCTION, NEW BRUNSWICK,
CANADA, AND WILLIS BLAKE HALL, OF CARIBOU, MAINE.

TRAIN-SIGNAL SYSTEM.

1,126,178.

Specification of Letters Patent.

Patented Jan. 26, 1915.

Application filed January 30, 1914. Serial No. 815,575.

To all whom it may concern:

Be it known that I, WILLIAM ERNEST BENN, a subject of the King of England, and a resident of McAdam Junction, in the 5 county of York and the Province of New Brunswick, Canada, (whose post-office address is McAdam Junction, New Brunswick,) have invented and discovered certain new and useful Improvements in Train-Signal Systems, of which the following is a specification.

The invention to be hereinafter described relates to train signal systems.

In order to more clearly disclose the construction, operation and use of the invention, reference should be had to the accompanying drawings forming part of the present application.

Throughout the several figures of the 20 drawings like reference characters designate the same parts.

In the drawings:—Figure 1 is a longitudinal cross section through an air brake pipe, showing the wiring; Fig. 2 is a cross-section on line 2—2 of Fig. 1; and Fig. 3 is a diagrammatic view of the system, complete.

The main objects of the system are to provide a simple, efficient, economical, compact 30 and durable signaling system which may be substituted for the present air signaling system without the many inconveniences and the considerable expense of air signaling system.

Referring to the drawings in detail, 1 indicates the upper and 2 the lower jaw of an air brake hose coupling. The upper jaw is cast separately and secured in place by a clamp 3. Between the jaws is seated a layer 40 of insulation 4. Within the hose are arranged the two wires 5 of an electric signal system, the positive wire being connected to one jaw and the negative to the other jaw. Thus, when all the couplings of a train have 45 been made, the circuit will be complete from end to end, including the necessary batteries and a signal bell in the engine cab. At various points in the system a push button or buttons may be placed for signaling purposes. Where the air brake hose enters the 50 storage cylinders, the wires are brought out and crossed through a block 6, in any well known manner.

It is thought that the construction, operation and use of the invention will be clear 55 from the preceding detailed description.

Changes may be made in the construction, arrangement, and disposition of the several parts of the invention without in any way departing from the field and scope of the 60 same, and it is meant to include all such within this application wherein only a preferred form has been disclosed.

Having fully described my invention, what I claim as new and desire to secure by 65 Letters Patent is:—

1. In combination, air brake hose sections, separate upper and lower coupling jaws connected to each of said sections, insulation between the upper and lower jaws of each section, electric conductors mounted within said hose sections and connected to said jaws, a signaling device included in the circuit of said conductors, and means for effectually connecting the positive and the 75 negative side of the circuit.

2. In combination, air brake hose sections, separate upper and lower coupling jaws connected to each of said sections, insulation between the upper and lower jaws of each 80 section, and electric conductors mounted within said hose sections and connected to said jaws.

3. In combination, air brake hose sections, separate upper and lower coupling jaws 85 connected to each of said sections, insulation between the upper and lower jaws of each section, electric conductors mounted within said hose sections and connected to said jaws, and a signaling device included in the 90 circuit of said conductors.

4. In combination, air brake hose sections having coupling members with separate upper and lower coupling jaws connected to each of said sections, insulation between the 95 upper and lower jaws of each section, electric conductors connected to said jaws, a signaling device included in the circuit of said conductors, and means for closing the circuit, substantially as set forth.

WILLIAM ERNEST BENN.
